UNITED STATES PATENT OFFICE

BENJAMIN P. SAUNDERS, OF PONTIAC, MICHIGAN

COMBINATION HOLDER

Application filed September 28, 1929. Serial No. 395,984.

My invention relates to a new and useful improvement in a combination holder adapted for mounting in a convenient position such as on the instrument board or other support in a vehicle to provide a means for holding a watch, pencil, pad, or other similar article.

It is an object of the present invention to provide a device of this class which will be simple in structure, economical of manufacture, and highly efficient in use.

Another object of the invention is the provision of a device of this class which may be mounted in a convenient place and on which the various articles held may be easily and quickly attached and detached.

Other objects will appear hereinafter.

The invention consists in the combination and arrangement of parts hereinafter described and claimed.

The invention will be best understood by a reference to the accompanying drawing which forms a part of this specification, and in which

25 Fig. 1 is a front elevational view of the invention.

Fig. 2 is a side elevational view of the invention.

Fig. 3 is a top plan view of the invention.

30 Fig. 4 is a sectional view taken on line 4—4 of Fig. 3.

The invention is formed from a strip of metal 7 having a tongue 8 punched therefrom and partly doubled upon itself. The lower 35 end of the member 7 is angularly turned to extend outwardly as at 9 and upwardly struck tongues 10 and 11 extend at opposite sides of the lateral arms 12 and 13, each of which is provided at its upper end with a pair of spaced wings 14 and 15.

40 Lying in engagement with the plate or strip 7 and secured thereto is a plate or strip 16 having the angularly turned portion 17 directed to lie below the portion 9 and 45 slightly inclined theretoward, the outer end of this angularly turned portion 17 being curved as at 18.

45 In use the device may be attached to a suitable support by means of screws or other fasteners projected through the plates 7 and

16. The tongues 10 and 11 together with the arms 12 and 13 and the wings 14 and 15 serve as a suitable support for a watch 19, the metal from which the device is made being resilient so that these arms 12 and 13 will 55 spring apart sufficiently to permit the insertion of a watch therebetween and serve to securely hold the watch in position. The tongue 8 will co-operate with the watch and the tongue 10 for retaining in position a 60 pencil which may be placed to lie in a horizontal plane across the member 9. The member 17 will serve to clamp a memorandum pad against the undersurface of the member 9. If desired the device may also 65 be clamped on a suitable support placed between the parts 17 and 9.

In this way there is provided a very simple and inexpensive holding device which serves a number of purposes and which may 70 be made in an attractive form.

While I have illustrated and described the preferred form of my invention, I do not wish to limit myself to the precise details of structure shown but desire to avail myself of 75 such variations and modifications as may come within the scope of the appended claim.

Having thus described my invention, what I claim as new and desire to secure by Letters 80 Patent is:

A device of the class described, comprising: a plate; a portion turned to extend angularly to said plate; lateral arms at opposite sides of said angularly turned portion 85 extending upwardly in spaced relation; a pair of tongues punched from said angularly turned portion and projected upwardly extending substantially at right angles to said lateral arms; and a clamping member extending below and in spaced relation to said angularly turned portion.

In testimony whereof I have signed the foregoing specification:

BENJAMIN P. SAUNDERS. 95
